UNITED STATES PATENT OFFICE.

PAUL RAY, OF CHAMPAIGN, ILLINOIS.

PIANO-BENCH.

1,245,967.

Specification of Letters Patent. Patented Nov. 6, 1917.

Application filed January 29, 1917. Serial No. 145,223.

To all whom it may concern:

Be it known that I, PAUL RAY, a citizen of the United States, residing at Champaign, in the county of Champaign and 5 State of Illinois, have invented certain new and useful Improvements in Piano-Benches; and I do declare the following to be a full, clear, and exact description of the invention, such as will enable others skilled in the art 10 to which it appertains to make and use the same.

This invention relates to new and useful improvements in benches provided with adjustable seats and the primary object of the 15 invention is to provide a piano bench with a seat adapted to be positioned above the same and which is adjustable longitudinally and vertically whereby it may be positioned directly in front of any part of the piano de- 20 sired.

Another object of this invention is to provide a device of this character which is simple and durable in construction, inexpensive to manufacture, and one which will be very 25 efficient in operation.

In the accompanying drawings:

Figure 1 represents a side elevation of my invention, parts being broken away and shown in section;

30 Fig. 2 is a top plan view of parts shown in Fig. 1;

Fig. 3 is a horizontal section taken on the plane of the line 3—3 of Fig. 1; and

35 Fig. 4 is a vertical transverse section taken on the plane of the line 4—4 of Fig. 1.

In describing my invention I shall refer to the drawings in which similar reference characters designate corresponding parts throughout the several views. The numeral 40 1 designates a piano bench of the usual type which is provided with supporting legs 2, and which has in its top 3 a longitudinally extending slot 4.

Beneath the top of the bench and secured 45 to the opposite sides of the same are longitudinally extending rails 5 which extend substantially the entire length of the bench. These rails 5 are adapted to support a movable carriage 6 which is positioned in the 50 bench 1 beneath the top 3. The movable carriage 6 is formed of a casting which includes a central body portion 7 having a vertical threaded opening 8 therethrough. The central body portion is provided with up- 55 wardly and outwardly extending spider arms 9 which have their outer ends bent outwardly

and disposed substantially parallel with the opposite sides of the bench. These arms are four in number, two at each side of the body portion of the carriage, and mounted in 60 bearings in the ends of the arms are wheels 10 which are adapted to engage the rails 5 on the opposite inner sides of the upper portion of the bench. Positioned above the top 3 of the bench is a seat 11 which is preferably of the ordinary flat type such as are commonly used for piano stools, and this seat is provided with a downwardly extending shank portion 12 which is externally threaded and which is adapted to project 70 through the slot 4 in the top of the bench and to be positioned in and engage the threaded opening 8 through the body of the carriage, which is disposed directly beneath this slot. This opening 8 in the carriage is 75 in vertical alinement with the slot so that it is easy to place the seat in position and when so positioned the same is vertically adjustable with respect to the carriage and consequently the bench.

In operation when the seat is positioned in the carriage as has been hereinbefore described, it is obvious that said carriage is movable longitudinally with respect to the bench because of the carriage being provided with wheels on its opposite sides positioned on the guide rails 5 in the upper portion of the bench. This allows the seat to be moved to any desired position in front of a piano, and furthermore owing to the 85 vertical adjustment of the seat above described the same may be raised and lowered according to the position desired by the player.

This type of adjustable seat need not necessarily be limited to a piano bench but is applicable for any number of uses. This construction affords a very economical and efficient device having a seat that is horizontally and vertically adjustable with respect to the support by which it is carried.

From the foregoing description of the construction and operation of my improved piano bench, the manner of applying the same to use, and the operation thereof will 105 be readily understood and it will be seen that I have provided a simple and efficient device of this character for carrying out the objects of the invention.

I claim as my invention:

1. A device of the class described provided with a bench having a top portion

110

adapted to be used as a seat throughout the entire length thereof, a relatively narrow longitudinally extending slot in said top, a carriage slidably mounted beneath said top, 5 and a secondary seat disposed above the bench and connected with the movable carriage through the slot whereby the seat is movable longitudinally on said bench.

2. A device of the class described comprising a bench having a top portion adapted to be used as a seat throughout the entire length thereof, a relatively narrow longitudinally extending slot in said top, longitudinally extending guide rails in said bench 15 beneath the top, a movable carriage provided with wheels mounted on said rails, a secondary seat disposed above said top of the bench and a downwardly extending shank on said seat extending through the slot and 20 into the carriage, and said shank being vertically adjustable with respect to said carriage.

3. A device of the class described comprising a bench having a top portion adapted to 25 be used as a seat throughout the entire

length thereof, a relatively narrow longitudinally extending slot in said top, longitudinally extending guide rails secured to the opposite sides of the bench beneath the top, a movable carriage including a central body 30 portion positioned in the bench beneath the top and provided with upwardly and outwardly extending spider arms, wheels mounted in the extremities of said arms and adapted to engage the guide rails, said body 35 of the carriage having a vertical opening therethrough disposed in alignment with the slot, a secondary seat disposed above the slot, and a downwardly extending shank on said seat extending through the slot and adjustably mounted in the opening in the body of the carriage. 40

In testimony whereof I have hereunto set my hand in the presence of two subscribing witnesses.

PAUL RAY.
